RACK FOR SAMPLE CASES

Irwin M. Ikelheimer, New York, N. Y.

Application November 19, 1947, Serial No. 786,952

1 Claim. (Cl. 211—87)

1 This invention relates to improvements in wardrobe or salesmen's sample cases, and more particularly to a telescoping rack therefor.

An object of the invention is to provide an improved form of salesmen's sample case with a sectional telescoping rack secured to two angularly disposed adjacent inner walls of the case, the same being telescoped within the case and the hinged case cover closed when the case is to be carried, and said rack when in use being extendable beyond the body limits of the case and having a vertically adjustable supporting leg at the outer end of the outermost section capable of being adjusted until its lower end engages and rests upon the inner surface of the open cover when extending at right angles to the upright body of the case.

Another object of the invention is to provide an improved extensible and telescoping rack construction for wardrobe or salesmen's sample cases, the same being telescoped within the limits of the case when not in use or while travelling, and said rack being formed with a plurality of telescoping sections, the outermost of said sections having a vertically adjustable supporting leg formed thereon at its outer end and disposed at right angles thereto, whereby said rack may be extended after the case has been opened to provide means for supporting a plurality of clothes hangers upon which articles such as coats, suits, trousers, skirts and so forth, to be displayed, will be supported.

A further object of the invention is to provide an improved telescoping sectional rack completely disposed within a wardrobe or salesmen's sample case when the case is closed, said rack sections being extendable beyond the limits of the case when its cover is opened, providing a supporting bar or rack for a plurality of clothes hangers, and said rack sections having means at their ends for limiting the distance each section may be pulled from or extended out of its adjacent surrounding rack section.

A still further object of the invention is to provide an improved garment case or salesmen's sample case formed with a telescoping rack for hangers, comprising a plurality of coaxially disposed rack sections having cooperating securing means for holding the sections in extended position, and a vertically adjustable rack supporting leg on the outer end of the section which is extendable the furthest distance outside of the case when open, said case and rack being highly efficient in operation, and relatively inexpensive to manufacture and assemble.

2 Other objects will appear to those skilled in the art to which it appertains as the description proceeds, both by direct reference thereto and by implication from the context.

In the accompanying drawing in which like numerals of reference indicate the same parts throughout the several views:

Figure 1 is a side elevation of the improved rack shown in extended position with its supporting case shown in open position and in section;

Figure 2 is an end elevation of the improved rack or front elevation of the case of Fig. 1 and with the front rim of the cover broken away;

Figure 3 is a perspective view of the improved rack shown above and in extended position;

Figure 4 is a longitudinal vertical sectional view taken through the improved rack and adjustable supporting leg thereof; and

Figure 5 is a side elevation of the improved rack shown in collapsed or telescoped position.

In carrying out the invention, there is provided a wardrobe or salesmen's garment case designated generally by the reference numeral 1, said case including a hollow body portion 2 and a front closure or cover 3 hinged at 4 to the front edge of a forwardly projecting lip 4a of the lower end 4b of the body portion 2.

The improved telescoping rack of the present invention includes a rear end support comprising a bracket plate 5 which may be suitably fastened to the inside surface of the back wall 6 of the body portion 2 adjacent to or in the vicinity of upper end wall 7 of the case 1.

A forward support for the rack is also provided, comprising an L-shaped bracket member 8 the longer leg whereof has an upper laterally extending or horizontally disposed attaching arm 9 secured to the under side of said upper end wall 7 of the case 1. The lower reach 8a of the L-bracket terminates with an upturned short leg 8b the upper end of which is welded at 10 to the under side of a hollow or tubular fixed section 11 of a telescopic portion of the rack for supporting said rack in permanently located and immovable position. The L-bracket clears the sides and top of the rack section to permit free sliding of the coat hanger hooks thereon. Within the rear end of fixed rack section 11 is provided

a support or head member 12 suitably fixed as by a diametric pin 12a, immovably to said fixed section 11 and also secured to the bracket plate 5 by screws 13 shown or equivalent fasteners, extending through said plate 5 and into said head member 12. Said plate 5 has its end por-

3

tion formed as a lateral boss of equal diameter to and in continuation of rack section 11 secured thereto so that the hooks of coat hangers can ride onto the boss from the rack section and vice versa.

The forward end of the fixed section 11 of the rack is of reduced diametric size thereby providing an annular construction constituting a stop or shoulder 14 for limiting outward displacement of the next adjacent or second rack section 15 within the said fixed section.

Said second rack section 15 is tubular in form and of slightly smaller diameter than the outer or fixed section 11 and is telescopically positioned at least in part in said fixed section 11 at all times. By virtue of the telescopic mounting, the said second section 15 may nest within the outer fixed section in retracted position or may project forwardly in extended position to thereby increase the effective length of the rack. To prevent separation of said sections, the inner section 15 is formed with an outwardly flared bell or peripheral shoulder 16 on its inner end, the same being of approximately the same diameter as the inside diameter of the fixed section 11 and of a size to engage and constitute a stop against the annular shoulder or stop 14 on the fixed section 11 when the section 15 is in its extended position.

The forward end of the second section 15 is formed with an annular constriction constituting a stop or shoulder 17, similar to the above described stop 14 of the fixed section 11, but of smaller diameter.

A third hollow or tubular rack section 18 is formed similarly to the rack section 15, and accordingly provides an enlarged bell 19 on its rear end slidable within section 15 and also provides a constriction 20 at its forward end, said bell and constriction each constituting a stop or shoulder. Said section 18 is telescopically received by and always in part within the tubular second rack section 15, and functioning to nest therein in retracted position and to project longitudinally therefrom in extended position.

A supporting leg 21 is formed in part by an inverted L-shaped forward section 21a the horizontal portion thereof being in part always within and telescopically carried at its rear end by the third hollow or tubular rack section 18, and is formed on its extreme rearward end with a flared locking shoulder 22 for locking engagement with the constriction or shoulder 20 on the section 18 when the rack is in extended position. This horizontal portion of the leg may likewise nest in its retracted position within the said third telescopic section 15.

A disk 23 of any desired material is disposed about the horizontal portion of the leg 21 at the forward part thereof, being suitably retained from displacement as by a pin 23a for limiting the most forward garment hanger 24 supported on the rack from sliding onto the vertical part of the leg. In order to adapt the rack to cases of varying height, a tubular sleeve 25 is constituted as a part of the vertical portion of said

4

leg and adjustable in relation to the vertical portion of said forward section 21a. Said vertical portion of the forward section 21 is shown provided with a plurality of transverse vertically spaced holes 26 any one of which may receive a locking pin 27 when brought into registration with a transverse hole 28 in sleeve 25 and through the desired hole 26. At the bottom of sleeve 25 is provided a foot member 29 adapted to rest upon and in contact with the inner surface of the case closure or cover 3 when in open position as shown in Figure 1 of the drawing.

Garments 30 to be displayed or hung on said rack will be supported upon the hangers 24, which in turn will be suspended from the rack and when said rack is in extended position the garments will be conveniently spread or spaced from each other due to the extended length of and capacity of the rack then provided.

After the display has been completed or the case is to be packed for travelling, the rack will be telescoped until the several movable sections are retracted or the rack collapsed to nesting position of its sections as shown in Figure 5 of the drawing, and the garments 30 packed in the case 1 and the closure or cover 3 closed.

While the preferred embodiment of the instant invention has been illustrated and described, it will be understood that it is not intended to limit the scope of the invention thereto as many minor changes in detail of construction may be resorted to without departure from the spirit of the invention.

I claim:

35. A telescoping rack for positioning within a sample case or the like having a hollow body and a closure hinged thereto, comprising a plurality of coaxially grouped tubular rack sections of successively decreasing diameters and each inner section being telescopically slidable in the next outer section, an attaching plate secured to the tubular rack section having the largest diameter and adapted to be fixed within said body, said plate having a cylindrical boss of equal diameter to and in continuation of said rack section of largest diameter, means for limiting the distance said telescopically slidable rack sections may be extended with respect to each other, and an inverted L-shaped supporting leg having a part thereof telescopically received within the tubular rack section of smallest diameter.
